(57) **CLAIM**

The ornamental design for a binaural headset, as shown and described.

DESCRIPTION

FIG. 1 is a lower front left perspective view of a binaural headset, the broken line drawings of a microphone boom, connecting cord, clip and connector herein are for illustrative purposes only and form no part of the claimed design. FIG. 2 is an upper front right perspective view of the binaural headset.

FIG. 3 is a left side elevational view of the binaural headset.

FIG. 4 is a front elevational view of the binaural headset.

FIG. 5 is a right side elevational view of the binaural headset.

FIG. 6 is a rear elevational view of the binaural headset.

FIG. 7 is a bottom plan view of the binaural headset; and,

FIG. 8 is a top plan view of the binaural headset.
